UNITED STATES PATENT OFFICE.

BENJAMIN F. GRAHAM, OF CHICAGO, ILLINOIS.

COLLAPSIBLE GRAIN-DOOR.

1,384,190.

Specification of Letters Patent. Patented July 12, 1921.

Application filed July 19, 1920. Serial No. 397,375.

To all whom it may concern:

Be it known that I, BENJAMIN F. GRAHAM, a citizen of the United States, residing at Chicago, in the county of Cook and 5 State of Illinois, have invented certain new and useful Improvements in Collapsible Grain-Doors; and I do hereby declare that the following is a full, clear, and exact description of the same, reference being had 10 to the accompanying drawings, and to the numerals of reference marked thereon, which form a part of this specification.

My invention relates to a collapsible grain door which is adapted to be placed in the 15 doorway of a freight car, and comprises mechanism whereby the same may be readily adjusted for different sizes of doorways, and mechanism whereby the same may be easily operated.

20 It is therefore an object of my invention to provide a collapsible door that may be readily adjusted for cars having different sized doorways by an easy and convenient method, and that is not liable to sag.

25 It is also an object of my invention to provide a collapsible door that is provided with overlapping hinge sections to strengthen the same and prevent the escape of small grain.

It is a further object of my invention to 30 provide a novel structure and arrangement that is cheap, durable and easily manipulated, as will more specifically appear from the following specification and disclosures in the drawings.

35 The invention (in a preferred form) is illustrated in the drawings and hereinafter more fully described.

On the drawings:

Figure 1 is a side elevation of a box car 40 showing the sliding door open with my collapsible doors mounted in the doorway.

Fig. 2 is a section on the line 2—2 of Fig. 1, on an enlarged scale, and also showing in dotted lines, the grain door in open 45 position.

Fig. 3 is a front elevation of my collapsible door on an enlarged scale.

Fig. 4 is an enlarged section of the adjustable mechanism from the rear side.

50 Fig. 5 is a fragmentary section of the door hinge on an enlarged scale.

Fig. 6 is a fragmentary sectional view showing the door adjustment at one end on line 6—6 of Fig. 3, on an enlarged scale.

55 Fig. 7 is a section on the line 7—7 of Fig. 1, on an enlarged scale.

Fig. 8 is a plan view of a modified form of adjustment.

Fig. 9 is a section on the line 9—9 of Fig. 8, on an enlarged scale.

As shown on the drawings:

Referring now to the drawings, in which similar reference numerals refer to similar features in the different views, 1 represents a box car in which grain may be hauled, and 65 2 represents the usual sliding door in open position. The open doorway of the car is shown as closed by a plurality of my improved collapsible doors, the lower one of which is the one usually used for emptying 70 the grain from the car, the others provide retaining boards for keeping the grain in the car.

My collapsible door comprises preferably a pair of fairly narrow boards 3, in alinement and arranged at the upper outer side of the door. These boards may consist of wood or other substance. Below these boards there is a pair of boards 4 of substantially twice the width of the narrow boards 75 and arranged similarly to the boards 3 with their abutting ends in alinement with the abutting ends of the boards 3. On the opposite side of the door are a pair of similarly alined narrow boards but arranged at the 80 lower part of the door, and a pair of similarly alined broad boards at the upper part of the door. The abutting ends of these narrow and broad boards are in alinement, but the line of juncture on one side is a trifle 85 to one side of the line of juncture of the boards on the opposite side or staggered 90 with relation thereto as shown in Figs. 3 and 5. As shown in Fig. 7, it will be observed that each broad board overlaps the 95 end of a narrow board and also the juncture of a broad board with a narrow board on the opposite side of the door; thus interfitting parts are provided and staggered joints whereby a rigid structure is attained that 100 precludes sagging to a large extent and the escape of grain. This structure provides an especially strong hinge joint and tends to prevent small grain from getting out between the hinged boards. Hinges 5 of any 105 approved design pivotally connect the boards on the inner line of juncture, allowing the pivoted boards to flex outwardly as shown. Since this flexing provides an opening for the grain to escape by gravity from the car, 110 it is necessary to provide means to prevent the door from flexing or opening except

when desired. Accordingly, I have provided a pivoted latch member 6 on the outer side of one door member, and an obliquely arranged latch keeper 7 on the outer side of the other door member. This latch member 6 is operated by means of a lever 8 pivoted at 9 upon the pivotal axis of the latch member 6. The lever 8 is provided with a handle portion 10 whereby it may be easily 10 swung to unlatch the member 6 from the keeper 7. Near one end of the door upon the inner side thereof there is firmly bolted, an abutment in the form of a joint 11, which limits the endwise movement of the door 15 with respect to the upright 12. Near the opposite end of the door there is an adjustable abutment in the form of a screw 13, having a head 13^a abutting against an upright 12^a, and threaded into the outstanding 20 flange 14 of an angle member. The other leg 15 of this angle member is adjustably secured to a plate 16, which is secured to the door over a cut out section 17, thereof (see Fig. 6). For this purpose the plate 16 is 25 provided with a plurality of inclined notches 18 and a groove 19, and the leg 15 is provided with a stud pin 20, adapted to fit in the notches 18, and a screw 21 having a head 22 in slidable engagement with the bottom 30 of the plate and a round boss 22^a fitting in the groove 19. The arrangement is such that the angle member may be swung or swiveled to bring the stud pin 20 into the groove 19, allowing the angle member to be 35 shifted longitudinally until the stud pin can be swung into a different notch. This adjustment may be called the major adjustment since it provides for adjustments incapable of being attained by the minor adjustment of the screw 13. Both of these 40 adjustments are simple and easily effected to accommodate my collapsible door for any variation in the width of car doors, and to also secure the door against endwise movement by the minor adjustment.

In Figs. 8 and 9, I have shown a modified form of adjustment in which a supporting plate 23 having a slot and ratchet teeth 24 in one wall thereof is secured over a groove 50 25 cut in the door. This groove is preferably made by removing a portion of one of the boards which constitute the door. This plate 23 supports an adjustable plate member 27 having a ratchet tooth 28 designed to 55 engage any of the teeth 24 on the plate 23. Plate member 27 is secured by means of a stud 28^a having a head 29, which fits against the rear of the plate 23 and is provided with a boss 30 that fits in the slot of plate 23 and 60 an aperture in plate 27. The outer end of stud 28 is further provided with a boss 31, upon which is pivoted a cam member 32 having an operating handle 33. The outer end of plate 27 slidably supports the abutment 65 34, which may assume the form of an angle

iron with the outstanding flange serving as the abutting surface. A slot 35 in the plate 27 is designed to receive the boss of a screw 36 having a flanged head 37 fitting against the rear of the plate 27, the threads of this 70 screw being designed to support the abutment 34 adjacent the cam member 32. The head 37 of the screw 36 has a sliding passage in the groove 26 of the door. The major adjustment in this instance is effected 75 by slightly turning the plate 27 and sliding it so as to engage the tooth 28 with a different tooth of the ratchet plate 23. The minor or supplemental adjustment is effected by operating the cam 32 against the end 80 of the abutment 34 to slide the same so as to wedge the same against the upright 12^a.

In order to prevent tampering with the grain in transit, my collapsible door may be locked and sealed in place, and for this purpose I have shown a wire 38 which extends 85 in back of the lever 6 and enters through an aperture 39 in the lever 6 and keeper 7, the ends of the wire being brought together and locked by seal 40.

In the use of my invention, it is contemplated that the doors locked from flexing may be placed in position one on top of the other in interfitting relation and adjusted against endwise movement as the car is being filled with grain. And when the car has reached its destination, the lower door may be unlatched by a downward swing upon the handle 10 whereby the co-operating lever 6 will move out of engagement with the keeper 7. The pressure of the grain in the car will then act to flex the door outwardly to allow the grain to escape. In case the pressure of the grain is not sufficient to flex the door open, some manual 105 means may be used to assist in the opening thereof.

It will accordingly be observed that my collapsible door embodies a strong and non-sagable structure that is easily and readily 110 adjustable; that for this purpose is provided with a major adjustment where the variation in the size of door is of a sufficient degree, and a minor adjustment that provides for small adjustments and at the same time 115 secures the door against endwise movement; that is easily and readily flexed and very serviceable for the use to which it is put.

I am aware that numerous details of construction may be varied through a wide 120 range without departing from the principles of this invention, and I therefore do not purpose limiting the patent granted otherwise than necessitated by the prior art.

I claim as my invention:

1. In a device of the class described, a collapsible door comprising a plurality of hinged sections, an abutment at the end of one section, and an adjustable abutment near the end of the other section comprising a 130

member adjustable by a turning and slidable movement and a longitudinally adjustable member carried thereby.

2. A collapsible grain door having an abutment at each end, one of said abutments comprising a longitudinally adjustable screw member, and an adjustable support for said member.

3. In a grain door, a supporting plate having a notched slot, a member slidably adjustable in said slot and having a lug cooperating with said notches to hold said member in adjusted position, and an adjustable device carried by said member to provide an adjustable abutment for the door.

4. A collapsible door for grain cars comprising a pair of sections hinged together, each section comprising a double tier of boards in overlapping relation with one tier of boards of each section overlapping a

tier of boards of the opposite section and disposed in staggered relation thereto to provide a double overlapping juncture at the hinge connection, and means for holding said sections in rigid relation.

25

5. A collapsible grain door for grain cars, having a slot adjacent one end, a support anchored in said slot and shiftable to different positions in said slot, and a device carried by said support and adjustable with respect thereto and adapted for engaging parts of the car wall.

In testimony whereof I have hereunto subscribed my name in the presence of two subscribing witnesses.
